UNITED STATES PATENT OFFICE.

JOHN F. FARRINGTON, OF NEW YORK, N. Y., ASSIGNOR TO WESTERN ELECTRIC COMPANY, INCORPORATED, OF NEW YORK, N. Y., A CORPORATION OF NEW YORK.

TWO-WAY COMMUNICATION SYSTEM.

Application filed December 23, 1920. Serial No. 432,644.

To all whom it may concern:

Be it known that I, JOHN F. FARRINGTON, a citizen of United States, residing at New York, in the county of Bronx and State of New York, have invented certain new and useful Improvements in Two-Way Communication Systems, of which the following is a full, clear, concise, and exact description.

10 This invention relates to a two-way signaling system, and more particularly to a two-way carrier wave signaling system. This application discloses matter first disclosed in an application of the same inventor, Serial No. 326,986, filed September 27, 1919, of which this application is accordingly a continuation in part.

15 Its object is broadly to provide to provide improved means for the simultaneous transmission and reception of signals by modulated carrier wave operation.

20 A more specific object is to accomplish the purpose stated by conjugately relating the transmitting and receiving circuits in such a manner that the balance is effected 25 between the signal frequency currents.

25 An additional object is to provide a two-way signaling system of the above mentioned type in which the transmitting oscillator combines its function as such with that of a detector. Other objects will be apparent from the following description.

30 The means for carrying out the functions stated above preferably includes conjugately related or balanced low frequency receiving and transmitting circuits, the high frequency receiving and transmitting circuits not being so related.

35 In the specific embodiment to be described in some detail later and which is illustrative of one form of conjugate arrangement, the low frequency modulating current is impressed on the divided primary circuit of a transformer across the secondary of which 40 may be connected a telephone receiver, the current from the low frequency source flows through the one-half of the primary to the high frequency oscillator. The oscillator and low frequency source being related 45 so as to constitute together a system of modulated high frequency wave generation commonly known as the constant current system of modulation. The usual high frequency choke coil is included in circuit with 50 the oscillator to prevent the flow of high

frequency current in the circuit of the modulating means. The low frequency current flows also in the other half of the primary winding and through an artificial network 55 adjusted to give a balance in the transformer secondary circuit with respect to the currents in the primaries. The system enables the generation and transmission of a modulated carrier wave without interfering side tone current in the related receiver.

60 Although the carrier frequency current in the receiver circuit due to unbalance of the conjugate system with respect to carrier current frequencies, would not result in interference with the signaling frequency 65 current, it would produce an undesirable heating effect in the circuit and, unless balanced, would also tend to cause variations in the contents of the circuits and make difficult a stable condition of balance. Accordingly, means is disclosed for balancing 70 when necessary, the low frequency circuits at carrier frequency as well as at low frequency. An advantage in the use of a low frequency balance inheres in the greater 75 facility with which the balance may be maintained.

75 The oscillator which constitutes an element of the above described system and in which the modulation occurs, is capable of 80 functioning also as a detector, constituting the system as described above, a two-way transmission system. Although it is recognized as broadly old to combine the functions of a modulator and detector in a single 85 device, it is believed to be novel to utilize the transmitting and generating tube as a detector of a signal frequency current in a system for simultaneous two-way operation. The arrangement as described results in a 90 simplicity of circuits and avoidance of expense incidental to the use of separate means for the two functions.

95 The invention will be more readily understood from a reading of the detailed description which follows, taken in connection with the accompanying drawing in which Fig. 1 shows one modified form of the system of the invention; Fig. 2 shows a system 100 similar to that of Fig. 1 except as including an alternative form of modulating and generating means; and Fig. 3 illustrates a modified form in which the two carrier frequencies may differ from each other.

105 Referring specifically to Fig. 1, the refer-

ence letters O, M, R and N designate respectively, an oscillator, modulator, receiver, and balancing network. The oscillator O and modulator M cooperate to generate a high frequency wave modulated in accordance with the low frequency signal impressed on the modulator input. The oscillator O is of a well known type working directly on the antenna 1. The antenna is related to the circuits of the tube in a manner well known. The frequency generated is determined by the natural frequency of the antenna circuit i. e. by the capacity of the radiating member, the inductance of the coil 3 and the capacity of the condenser 4. The adjustable connection constituting the plate coupling between the antenna loading coil 3 and the plate circuit of the generating tube provides a means for adjustment of the feed-back coupling without changing the frequency of the generated oscillations. A grid leak path including a capacity, a resistance and an inductance, the two first mentioned being in parallel with each other and in series with the inductance, is connected between the grid and filament of tube 2. Space current for the tube 2 is furnished by the source 5 through the speech frequency choke coil 6, one winding L_1 of the primary of transformer T, and high frequency choke coil 7. Shunted around the source 5 and coil 6 is the anode and cathode path of the vacuum tube 8. The input circuit 9 of the tube 8 is coupled to the microphone circuit 10 which is representative of any suitable source of speech or other signaling frequency electrical waves or variations. The production of speech waves in the circuit 10 will cause a corresponding variation in the impedance of tube 8 which will in turn cause variation in the currents supplied to the tube 2. The choke coil 6 keeps the current flow from the battery 5 substantially constant. The oscillator O and the modulator M cooperate to generate a modulated carrier wave according to a method commonly known as a choke control, constant current modulating system. The coil 7 substantially excludes the high frequency oscillations from the modulating circuit including coils L_1 and L_2 .

The artificial net-work N receives current from the modulating amplifier through the coil L_2 of the primary winding of the transformer T and is so designed that the currents circulating in coils L_1 and L_2 will have equal and opposite effects upon the secondary circuit of transformer T.

In the system of Fig. 1, the network N is of novel type by means of which there is obtained a balance of currents in the transformer primary due both to the low frequency variations of current in the output of modulator tube 8 and high frequency oscillations derived from oscillator O. This insures a balance with respect to such high

frequency current as may pass through choke coil 7. The circuits of the network have not only been made the exact duplicates of the oscillator circuits in circuit with winding L_1 so far as regards the impedance characteristics, but the tube 2 with its various connections is also duplicated. The network therefore functions as an actual oscillator whose oscillations are utilized to effect a balance of the high frequency currents from the oscillator O which pass the choke coil 7. The designation "dummy oscillator" is applied to that form of balancing circuit which is capable of this function in addition to that of an impedance balance. The telephone receiver 11 or other indicating means, may be connected directly across the secondary L_3 of the transformer but is here shown as inductively coupled with the output of an amplifier A. Accordingly, by means of the circuit arrangements so far described, signals originating in circuit 10 may be transmitted to a distant communicating station as modulations of a high frequency current wave, all without interference with the circuits R.

In receiving, the oscillator O combines its function as a generator of waves of carrier frequency with that of a detector by means of which a modulated carrier wave is resolved into components including one having the characteristics of the modulating wave at the distant station. This low frequency wave may readily be transmitted through the high frequency choke coil 7. Arrows are shown adjacent the antenna to indicate its functions as a receiving and transmitting conductor f_1 denoting the outgoing frequency and f_2 the incoming. By reason of the oscillating characteristic of the detecting circuit, the well known self-amplifying effect is secured. The low frequency detected current flows through windings L_1 and L_2 and network N. This current is unbalanced with respect to the secondary L_3 and therefore causes a response in receiver R. The network N and transformer T may be provided as a protection with grounded electrostatic shields in conformity with what has been found to be the best practice in that regard.

The system of Fig. 2 differs from that of Fig. 1 principally in the particular generating and transmitting means employed and the substitution for the dummy oscillator of Fig. 1 of an artificial network designed to produce a balance with respect to low frequencies. It is of well known type and comprises the necessary impedance elements to produce the desired balance. The systems of the two figures function in much the same manner and the two forms of networks shown, as well as the specific generating and transmitting means, may be used interchangeably. The network of Fig. 1, how-

ever, has the additional function described above. Only so much of the system of Fig. 2 will be described below as is necessary to an understanding of the transmitting and generating circuits referred to.

In particular cases it may be desirable to maintain a constancy of oscillation greater than can be secured by the means shown in Fig. 1, in which the oscillator oscillates directly into the antenna, and in which the modulating function occurs in the oscillator. The means of Fig. 2 differs from that of Fig. 1 in that the oscillator oscillates into the input of the amplifier A_1 which in turn works into the antenna 1. The frequency of oscillation is determined by the constants of the circuit comprising an inductance 12 and the capacity of condensers 13 and 14. The remaining condensers shown function as stopping condensers for the space current or as grid condensers in accordance with a well known principle. Space current for the oscillator is provided directly by the battery 5 without the interposition of a low frequency choke coil, the modulating function occurring on the amplifying tube A_1 which receives its space current from source 5 through low frequency choke 6 in the same manner as the oscillator receives current in Fig. 1. For a more detailed disclosure of a modulation system of this type, reference is made to U. S. Patent to Raymond A. Heising 1,442,147, January 16, 1923, in which such a system is described and claimed.

Fig. 3 illustrates a modified form of the system of Fig. 1, which provides means for applying the principle of the invention to the case where different carrier frequencies are used for sending and receiving. Although in general, the arrangement of Fig. 1 combines the elements of simplicity, low cost and utility to a maximum degree, it is evident that its effectiveness in a large part is dependent on the accuracy with which the two carrier frequencies may be maintained equal, inasmuch as, if the frequencies become slightly different, the detecting action of the tube 2 would result in a component of current having a difference frequency which would in the usual case be well within the audible range, and would cause, at the best, an undesirable side tone in the receiver. The system of Fig. 3 avoids the necessity of a close correspondence of the carrier frequencies by permitting them to differ by an amount which will cause the difference frequency current to be inaudible and so not to interfere with the reception of the signals. The difference frequency component and the modulated difference frequency component may be suppressed, if desired, by the band filter FB which is adjusted to pass only the frequency signal component. In this figure the telephone receiver 11 is shown directly across the amplifier output although the cor-

responding means shown in Fig. 1 may equally well be used. Also an artificial network of a conventional type has been substituted for the dummy oscillator of Fig. 1.

In order to provide for the case in which the antenna cannot be tuned broadly enough to send and receive effectively the currents of the two frequencies, the circuit means shown at the left of the antenna may be used. By means of the circuit designated generally by 15 in shunt with elements 3 and 4, the antenna is made resonant to the frequency of the received wave. The resonant circuit 16 is tuned to the frequency of the transmitted wave and effectively excludes currents of this frequency from the branch circuit. The arrangement results in giving the antenna system two degrees of freedom.

The novel features which are believed to be inherent in the invention are defined in the appended claims.

What is claimed is:

1. A station for two-way communication systems comprising in combination a transmitting circuit and a receiving circuit, including a transmitting and receiving conductor, common means for generating the outgoing high frequency carrier wave and for detecting the incoming modulated carrier wave associated in energy transfer relation with said conductor, a modulating circuit associated with said means for modulating said high frequency wave, a receiving device, and means conjugately relating portions of said transmitting and receiving circuits, whereby transmission may be effected without interference with reception.

2. A station for two-way communication systems comprising in combination a transmitting and receiving conductor, a combined oscillating and detecting means of the thermionic vacuum tube type associated therewith, including a space current source and coupled input and output circuits, a transformer having a secondary, and a divided primary, winding, a low frequency choke coil, a portion of said divided transformer primary winding and the space current circuit of said means being in circuit with said space current source, a low frequency source in shunt with said low frequency choke coil, another portion of said divided primary winding being in circuit with said space current source and said choke coil, said portions being oppositely arranged with respect to the secondary winding, a receiving means in circuit with the secondary winding, and circuit means included in circuit with said second portion whereby the currents in said portions from said low frequency source are balanced with respect to said secondary.

3. The system of claim 2 in which the said circuit means is an oscillator adapted to generate a wave similar in form and amplitude to that generated by said oscillating means.

4. A station for two-way radio communication systems comprising in combination, a transmitting and receiving antenna, a combined oscillating and detecting means of the thermionic relay type associated therewith including a space current source and coupled input and output circuits, a transformer having a secondary, and a divided primary, winding, a low frequency choke coil, a portion of said divided transformer primary winding and the space current circuit of said means being in circuit with said source and means, a low frequency source in shunt with said low frequency choke coil, another portion of said divided primary winding in circuit with said space current source and said choke coil, said portions being oppositely arranged with respect to the secondary winding, a receiving means connected across the secondary winding, and circuit means included in circuit with said second portion whereby the currents in said portions are balanced with respect to said secondary.
5. The system of claim 4 in which said circuit means comprises an oscillation generator.
6. A carrier wave transmission system comprising a transmission circuit, means connected to said circuit in energy transfer relation for generating a high frequency carrier wave and detecting an incoming modulated carrier wave, a circuit for transmitting modulating currents to and detecting modulated current from said means, a modulating source in energy transfer relation to said last mentioned circuit, a receiving device in energy transfer relation to said last mentioned circuit, and balancing means for preventing the modulating current from affecting said receiving device.
7. A carrier wave transmission system comprising in combination, a transmitting and receiving conductor, common means associated with said conductor for generating a high frequency carrier wave and for detecting the modulated carrier wave received over said conductor, a receiving device asso-

ciated with said detecting means, modulating means associated with said conductor and receiving device, and means conjugately relating said modulating means and receiving device.

8. In combination, two closed circuits, each containing an individual and a common portion, the individual portion of one of said circuits comprising means for generating and transmitting an alternating current wave and the individual portion of the other circuit comprising a current balancing network including independent alternating current generating means, the constants of said balancing network being so adjusted as to cause its impedance, and its generated current with respect to the common portion to be substantial duplicates of the impedance and generated current in the individual portion of said first mentioned circuit.

9. In a carrier wave transmission system, a transmitting circuit, common means connected in energy transfer relation to said circuit for generating a high frequency outgoing wave and for detecting a modulated carrier incoming wave, a modulating source and a receiving means associated with said common means and circuits causing said source and receiving means to be conjugately related, said circuits functioning as a balancing impedance which generates oscillations.

10. In combination, a transmitting oscillator, means for controlling said oscillator in accordance with signals, a balancing oscillator, said oscillators being connected to said controlling means, and a receiving device electrically connected to said oscillators in opposite senses with respect to said controlling means, whereby outgoing signals from said controlling means are neutralized in their effect on said receiver.

In witness whereof, I hereunto subscribe my name this 16th day of December A. D., 1920.

JOHN F. FARRINGTON.
